UNITED STATES PATENT OFFICE.

EMANUEL J. GRACE, OF ERIE, PENNSYLVANIA.

DISPENSING MECHANISM.

Original application filed February 25, 1921, Serial No. 447,634. Divided and this application filed April 2, 1923. Serial No. 629,293.

To all whom it may concern:

Be it known that I, EMANUEL J. GRACE, a citizen of the United States, residing at Erie, in the county of Erie and State of Pennsylvania, have invented certain new and useful Improvements in Dispensing Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to dispensing devices for dispensing grease for motor vehicles.

This invention was originally shown and described in my application for patent filed February 25, 1921, Serial No. 447,634 of which this is a divisional application.

The object of this invention is to provide dispensing mechanism adapted to measure the material as it is being delivered, and to provide suitable means for accurately adjusting the measuring mechanism. Also to provide means whereby the operating mechanism can be adjusted without disarranging the measuring mechanism.

These and other features of my invention are hereinafter set forth and pointed out and are illustrated in the accompanying drawings in which:

Figure 1, is a side elevation of my improved dispensing mechanism.

Figure 2, is a plan view of the same.

Figure 3, is a central transverse section of the cover of the container tank.

Figure 4, is a vertical central section of the measuring mechanism enlarged.

In these drawings A indicates the base, which is provided with wheels a at one end, and with a leg a' at the other end thereof. Upon one end of the base A is placed a container B which communicates with a passage in the base A, shown in broken lines in Fig. 1, leading to the pump C of ordinary construction, mounted on the other end of the base A. From the pump C, a tube C' leads

to a connection C², to which a flexible tube C³ is connected. The opposite end of the flexible tube C³ is provided with a shut off valve c to which an L-shaped nozzle is secured. The upper end of the container C

has an open or slotted ear b' adapted to receive the L-shaped nozzle D. From the connection C² an upright post C⁴ extends upwardly and has secured thereon a journal bearing E, and upon the journal bearing E another post C⁵ extends upwardly. The flange b on the upper end of the container is provided with a horizontal extension b² through which the post C⁵ extends, and to which said post is secured by means of a set screw b³. Mounted in the bearing E is an eccentric sleeve F in which a crank shaft G is placed. Upon this crank shaft G is a sprocket wheel g from which a chain g' extends to a sprocket wheel c' upon the pump shaft c². The inner end of the eccentric sleeve F is provided with a circular flange f see Fig. 4, which is concentric with the axis of the crank shaft G, and upon this flange f a plate H is mounted, so that when the eccentric sleeve F is rotated in its bearing E, the plate H moves in unison with the shaft G. Upon the inner end of the shaft G, I secure a disc G', for the purpose hereinafter set forth. This disc G' also acts to maintain the plate H in contact with the inner flat side e of the journal bearing E. From the upper end of the plate H, an arm h extends inwardly over the disc G' to a vertical sleeve J, which extends upwardly through an opening in the lateral extension b² of the flange b, by which the plate H is maintained in a vertical position.

Upon the upper side of the arm h there are ears h' to which an arm K is pivoted which extends through an opening in the wall of the sleeve J, to a weight K'. Mounted in the weight K' is a vertical hollow screw L, provided at its lower end with a thumb-nut by means of which the same may be turned when desired.

Within the hollow screw L a shaft M is placed, upon the upper end of which a disc M' is secured adapted to revolve within the upper end of the sleeve J. On the lower end of the shaft M is secured a friction wheel N adapted to contact with the disc G' the gravity of the parts acting to press the wheel N against the disc G'.

In order to maintain the apparatus in adjustment so that the pump C will operate in accurate relation to the measuring mechanism it is necessary that the chain g' be maintained sufficiently taut so that there will be no lost motion between the crank shaft G

and the pump shaft c^2 ; and for that purpose I have provided the eccentric sleeve F, which is shown in Fig. 4 in its uppermost throw. When the chain is first put on, the eccentric 5 sleeve F should be turned to its lowermost throw, exactly opposite to the position in Fig. 4. When this is done the plate H and the mechanism supported thereon together with the shaft G and disc G' move downward 10 in unison, so that the relative position of the disc G' and friction wheel N remain unchanged. Then as the crank shaft G is raised from time to time, by adjustment of the eccentric sleeve F the plate H and mechanism supported thereon will be raised in unison. 15

Upon the extension b^2 of the flange b are upright ears b^4 to which arms P of the cover P' of the container B are pivoted. The 20 cover P' is provided with an extension p which extends over the open slotted ear b' and covers and retains the L-shaped nozzle of the flexible tube C³ therein so that when the cover is locked down by the pad-lock Q, 25 unauthorized persons cannot operate the mechanism to filch from the contents of the container. When the cover P' is raised the tube C³ can be disengaged from the ear b'. This not only provides a support for the free 30 end of the tube C³ when not in use, but provides a secure means for locking the mechanism against theft of material. If the mechanism is operated while it is locked, the material runs from the nozzle D back 35 into the container. On the upper end of the sleeve J are placed characters to indicate the quantity of material dispensed, and on the disc M' is an indicator which points to the characters. This arrangement may be 40 reversed if desired.

The bearing E is provided with clamping ears e' through which a clamping bolt (not shown) may be placed, by means of which the eccentric sleeve F may be secured against 45 accidental rotation.

Having thus fully described my invention so that others can utilize the same, I do not desire to limit myself to the exact construction shown and described as many modifications 50 can be made therein without departing from the scope of my invention, therefore, what I desire to secure by Letters Patent is:

1. In a mechanism of the class described, 55 a pump, a pump shaft, a power shaft bearing supported above said pump, a power shaft mounted in said bearing, a frame supported on said shaft bearing, a vertical shaft mounted in said frame, an indicator disc on the upper end of said shaft, co-acting friction 60 mechanism on said vertical shaft and said power shaft, and means to communicate power from said power shaft to said pump shaft.

2. In a mechanism of the class described, 65 a pump, a pump shaft, a power shaft bear-

ing supported above said pump, a power shaft mounted in said bearing, a frame supported in said bearing, a vertical hollow screw mounted in said frame, a vertical shaft in said screw, an indicator disc on the upper end of said shaft, co-acting friction mechanism on said vertical shaft and said power shaft, and means to communicate power from said power shaft to said pump shaft. 70

3. In a mechanism of the class set forth, a pump, a pump shaft, a journal bearing supported above said pump, an eccentric sleeve in said bearing, a power shaft mounted in said sleeve, a frame supported on said journal bearing and adapted to have unitary vertical motion with said power shaft, a vertical shaft mounted in said frame, an indicator disc secured on the upper end of said shaft, co-acting friction mechanism on said vertical shaft and said power shaft, and sprocket chain mechanism on said power shaft and said pump shaft. 75

4. In a mechanism of the class described, a pump, a pump shaft, a bearing supported above said pump, a power shaft mounted in said bearing, a plate supported on said bearing, a vertical sleeve supported on said plate, a vertical shaft bearing within said sleeve and pivoted on said plate outside of said sleeve, an indicator disc on the upper end of said vertical shaft, co-acting friction mechanism on said vertical shaft and said power shaft, and means to communicate power from said power shaft to said pump shaft. 80

5. In a machine of the class described, a pump, a pump operating shaft, a chain and sprocket mechanism connecting said shaft with one of the pump cylinders, an adjustable eccentric bearing for said shaft, a vertically sliding frame engaging said eccentric and movable thereby, indicating mechanism mounted in said frame adapted to be adjusted by said eccentric, and an adjustable disc engaging a disc on the end of the pump operating shaft for operating the indicating mechanism. 85

6. In a mechanism of the class described, a pump, a pump operating shaft, an upright post, a crank-shaft, an adjustable eccentric bearing for said crank-shaft, sprocket wheels on said shafts, a chain operating on said wheels, a frame slidably mounted on said upright post and engaging said eccentric bearings and movable thereby, indicating mechanism mounted in said frame adapted to be adjusted by said eccentric, and means operable by said crank-shaft to operate said indicating mechanism. 90

7. In a mechanism of the class described, a pump, an upright post, a shaft bearing secured thereon, a horizontal crank-shaft mounted in said bearing, a vertical shaft bearing hinged on said horizontal shaft bearing, co-acting discs on said shafts, an indi- 95

cator disc on said vertical shaft, and means to operate said pump from said crank-shaft, whereby said indicator disc, and said pump are given relative movement.

- 5 8. In a mechanism of the class described, a pump, an upright post, a horizontal journal bearing secured on said post, an eccentric shaft bearing in said journal bearing, a crank-shaft mounted in said eccentric bearing, a frame slidably secured on said post, and adapted to be slidably operated by said eccentric and having a vertical cylindrical recess therein, a bracket pivoted on said frame and extending into said recess, a vertically adjustable shaft bearing mounted in said bracket, a vertical shaft mounted in said bearing, an indicator disc on said crank-shaft and said vertical shaft adapted to rotate the same, and means operable by said 20 crank-shaft to operate said pump with relation to said indicator.

9. In a machine of the class described, a container, a dispensing tube, a nozzle on said tube, an outturned slotted ear at the upper end of said container, adapted to receive 25 said nozzle, a cover for said container, a projection on said cover adapted to extend over said outturned ear and retain said nozzle therein, and means to secure said cover on said container.

30 10. In a machine of the class described, a container, a dispensing tube, a nozzle on said tube, an outturned slotted ear at the upper end of said container adapted to receive and support said nozzle, a cover for said 35 container adapted to enclose said nozzle when inserted in said slotted ear and retain the same therein, and means to secure said cover on said container.

In testimony whereof I affix my signature.

EMANUEL J. GRACE.
